UNITED STATES PATENT OFFICE.

DANIEL A. KEATING, OF BRIDGEPORT, AND JAMES B. TATEM, OF PUTNAM, CONNECTICUT, ASSIGNORS OF ONE-HALF TO THE AMERICAN TUBE & STAMPING COMPANY, OF BRIDGEPORT, CONNECTICUT, A CORPORATION OF CONNECTICUT, AND ONE-HALF TO JAMES B. TATEM, DOING BUSINESS AS JAMES B. TATEM & SON, OF PUTNAM, CONNECTICUT.

PICKER STICK.

Original application filed June 19, 1924, Serial No. 720,954. Divided and this application filed December 27, 1924. Serial No. 758,337.

To all whom it may concern:

Be it known that we, DANIEL A. KEATING and JAMES B. TATEM, citizens of the United States, residing at Bridgeport and Putnam, respectively, in the counties of Fairfield and Windham, respectively, and State of Connecticut, have invented certain new and useful Improvements in Picker Sticks, of which the following is a specification.

10 This case is a division of application No. 720,954.

This invention relates to an improved construction of combination wood and metal picker stick of the type employed to drive the shuttle across a loom; and the object of 15 this invention is the provision of a picker stick of this character having its upper end portion of wood and its lower end portion of metal, the metal being primarily for the purpose of strengthening that portion of the stick which ordinarily breaks first, while the upper or wooden portion is for the purpose of providing the flexibility required in a picker stick.

20 A further object of this invention is to provide the lower portion of the stick of metal formed into channel shape, the upper end of this metal portion being shaped to receive the lower end of the wooden upper portion and support its front and rear edges against the hammering shocks of the shuttle.

The invention further consists in the provision of a stiffening member which may be 25 formed integral with the lower end of the metal portion and shaped to provide proper bearings for the pivot pin when the stick is designed to be oscillated on a pivot or bolt.

30 With these and other objects in view, the invention consists of certain novel features of construction, as will be more fully described, and particularly pointed out in the appended claims.

45 In the accompanying drawings:

Figure 1 is a side elevation showing our improved construction of picker stick, the

upper portion being wood and its lower portion metal in channel form.

Figure 2 is a side elevation of our improved construction of picker stick.

Figure 3 is an enlarged sectional end view of the pivoted end of the stick on line 3—3 of Figure 1.

Figure 4 is a sectional end view of the stick on line 4—4 of Figure 1.

Figure 5 is a view showing one shape of lower end of the metal channel member as cut from sheet stock before being folded.

It is found in the practical construction and operation of picker sticks that, when made entirely of wood, their operating life, owing to the severe hammering strains to which they are subjected, is very short, and it is also found of advantage to strengthen the lower portion of the picker stick to prevent excessively rapid deterioration. It is also found necessary in the construction of picker sticks to provide a certain degree of resiliency which has heretofore been found in the usual picker stick of hickory. Therefore, in order to obtain at once, the required strength and also the yieldability, we have formed a picker stick having its upper portion of wood where the greatest resiliency is required, and its lower portion of metal where its greatest strength is required. By this construction, when one portion of the stick is destroyed a fresh part may replace the broken one and connected to the unbroken portion and the following is a detailed description of one embodiment of our invention by which these advantageous results may be obtained:—

With reference to the drawings, 10 designates the upper portion of our improved construction of picker stick, which is formed of wood, usually hickory, the same being preferably rectangular in cross section, larger at its lower end 11 and tapering towards its upper end 12.

This wooden portion is preferably formed of a length substantially one half of the entire stick but we do not wish to be limited

to any particular proportions as its length may be of any desired proportion of the whole length of the stick. The lower member of our improved picker stick is herein shown as being in channel form as at 13, the body portion of the channel member being preferably left open. This channel-shaped member may be formed in any desired manner, of any desired material and of any desired shape in cross section, but we preferably form the same of sheet metal and fold this metal to provide one side wall 14, a rear wall or flange 15, and a front wall or flange 16.

15 The upper end of this channel member is preferably formed so that its walls will receive and embrace the lower end 11 of the wood, and the front and rear walls 15 and 16, respectively, are arranged to provide a substantial backing to both the front and rear edges of the wood to support the same while acting upon the shuttle. This stick is preferably secured in the upper end of the channel member by means of bolts or rivets 17.

20 When this picker stick is designed to be mounted upon a pivot pin, we preferably reinforce its lower end in various ways to receive and support the pivot pin on which it is designed to oscillate.

25 Our preferred method of constructing this additional bearing portion is by providing an elongated integral tongue member 24 on the end of the side wall 14 and folding this tongue first laterally to provide an end wall 25 and then longitudinally of the channel to provide an opposite wall 26 which portion is adapted to set in between the front and rear edge walls 15 and 16 of the main channel member and these side walls 14 and 26 may be then pierced as at 29 and the stock about the piercing turned inwardly as at 30 to provide extending bearings for the pivot pin.

30 45 We do not wish to be limited to forming the foldable portion in the end of the side wall of the channel member, as this foldable portion may be formed in the edge of either the flanges 15 or 16, if desired; as illustrated at 31 in dotted lines in Figure 5 of the drawings, thereby providing an integral portion of the channel member adjacent its end adapted to be folded to form a short bearing side adapted to be pierced to provide a double bearing for the pivot pin on which the stick may swing.

50 55 We do not wish to be limited to mounting our improved picker stick to oscillate upon a pivot pin as other suitable means for supporting the lower end may be employed.

60 A picker stick of our improved construction is very simple and practical to manufacture, is effective in its operation and its working life over that of the usual all-wood

picker stick is greatly extended and at the same time it provides the required resiliency for receiving the shocks and effecting the throw of the shuttle.

The foregoing description is directed solely towards the construction illustrated, but we desire it to be understood that we reserve the privilege of resorting to all the mechanical changes to which the device is susceptible, the invention being defined and limited only by the terms of the appended claims.

We claim:

1. A picker stick having its upper portion of wood and its lower portion of a single piece of metal channel-shaped in cross section and having its lower portion folded to provide opposite spaced-apart integral side walls.

2. A picker stick having its upper portion of wood and its lower portion of a single piece of metal channel form in cross section and having an integral portion adjacent its lower end folded to cover the channel for a short distance and provide spaced-apart double bearing side walls.

3. A picker stick having its upper portion of wood and its lower portion formed of a single piece of sheet metal with its body portion folded into channel form and its lower end portion folded to have spaced-apart oppositely disposed side walls and edge walls.

4. A picker stick having its upper portion of wood and its lower portion formed of a single piece of sheet metal with its body portion folded into channel form and its lower end portion folded to have spaced-apart oppositely disposed side walls and edge walls and an end wall.

5. A picker stick having its upper portion of wood and its lower portion of metal channel-shaped in cross section, a tongue portion integral with the lower end of the side wall portion of said channel member folded to form an end wall and a short opposite side wall portion.

6. A picker stick having its upper portion of wood and its lower portion of metal channel-shaped in cross section, a tongue portion integral with the lower end of the side wall portion of said channel member folded to form an end wall and a short opposite side wall portion, said opposite side walls being pierced to receive and provide a bearing for a pivot pin.

7. A picker stick having substantially its upper half of wood and its lower half of a single piece of sheet metal having its body portion folded into channel form and shaped at its upper end to closely embrace the lower end of the wooden portion, and its lower end having a portion folded to form a short opposite side wall.

8. A picker stick having substantially its upper half of wood and its lower half of a single piece of sheet metal having its body portion folded into channel form and shaped at its upper end to closely embrace the lower end of the wooden portion, and its lower end having a portion folded to form a short

opposite side wall, both of the side walls having cooperating pivot pin receiving holes with extended bearing portions.

In testimony whereof we affix our signatures.

DANIEL A. KEATING.
JAMES B. TATEM.
